UNITED STATES PATENT OFFICE.

ANSEL J. DAYTON, OF TACOMA, WASHINGTON.

AMUSEMENT APPARATUS.

No. 857,605.

Specification of Letters Patent.

Patented June 25, 1907.

Application filed June 1, 1906. Serial No. 319,743.

To all whom it may concern:

Be it known that I, ANSEL J. DAYTON, a citizen of the United States of America, residing at Tacoma, in the county of Pierce and State of Washington, have invented certain new and useful Improvements in Amusement Apparatus, of which the following is a specification, reference being had therein to the accompanying drawing.

10 This invention relates to amusement apparatus and especially to merry-go-rounds and has for its objects to provide a device which shall be propelled by the riders, and which will resemble the action of rowing.

15 A further object is to provide an automatic friction brake which shall be more sensitive to the rotary action of the machine than would be the case if it relied solely on its centrifugal action, and which can be adjusted so that any desired degree of sensitivity may be secured.

I attain these objects by the devices illustrated in the accompanying drawing, in which

25 Figure 1 is a vertical cross-section of my machine, Fig. 2 is a plan thereof, Fig. 3 is a plan of the antifriction disk, Fig. 4 is an elevation of the propelling oar, and Fig. 5 is an elevation of the automatic brake.

30 Similar numerals of reference refer to similar parts throughout the several views.

The base "1" of the apparatus has the column "2," supporting the table "3," secured to it and is suitably mounted on foundations. The table "3" is circular in form and is provided with a number of radial flanges "4" extending from near the center of the table to its outer edge.

An antifriction disk "5" is supported on 40 balls "6" which pass through it and support the main seat disk "7." The disk "5" surrounds the central column "2" and is provided with vertical rollers "8" bearing against said column and mounted on pins secured to said disk "5." The seat disk "7" bears on the balls "6" and is supported thereby and is kept concentric with the apparatus by bearing against the outer side of the rollers "8." The disk "7" travels twice as fast 45 as the disk "5" since it is supported on the balls "6," and the same relationship exists at the center since the rollers "8" are mounted on pins secured to the disk "5" and bear against the fixed column "2" and the inner 55 edge of the disk "7." A series of suitable

seats "9" are secured to the disk "7" being arranged radially thereon, and each of the seats is provided with a suitable swivel oar-lock "10." The propelling oars "11" fit loosely in the oar-lock "10" and are provided at their outer ends with wheels "12." These oars are adapted to engage with their wheeled ends the flanges "4" on the table "3" and to roll along said flanges as the disk "7" rotates and they swing in the oar locks "10." Thus it will be seen that persons seated on the seats "9" can drive the merry-go-round by means of the oars "11" since the central table "3" is stationary; and further the speed with which the merry-go-round will rotate will depend entirely on the effort exerted by those riding thereon. It will be seen that in the drawings I have shown the central table provided with eight radial flanges "4" while the disk "7" has six rowing seats "9" secured thereto. Hence I am able to make the motion of the disk "7" very steady as adjacent rowers will be in different parts of their strokes while opposite rowers will be in similar positions, so that while one pair of opposite rowers are recovering and preparing to take a new stroke the other pairs are in the middle or near the end respectively of their strokes.

The speed of rotation of the disk "7" is further regulated by means of a pair of frictional governors consisting of a shoe "13" carried by the disk "7" and adapted to bear against the upper surface of the base "1" when pressed downward by the governor. This shoe "13" is secured to a vertically moving rod "14" which is secured to the swinging lever "15" of the governor, said lever "15" being pivoted to the frame "16" which is mounted on the disk "7." The outer end of the lever "15" is bent downward almost vertically so as to assume an almost vertical position and is provided with a weight "17" at its end and with a wing "18" between the weight "17" and the pivot. This wing "18" is clamped to the lever "15" by suitable straps "19" in such a manner that its angle to the radius of the disk "7" may be varied by loosening the clamps "19" and adjusting the wing "18" to the desired angle and then tightening up the clamps "19." As the disk "7" rotates the weight "17" tends to fly outward through the action of its centrifugal force, but since the amount of motion necessary to effect the regulation of the disk

would require either that the disk rotate at a greater speed than would be convenient for this merry-go-round, or that the weight "17" be too great for practical purposes. Hence I 5 have combined with the action of the weight "17" the aiding action of the wing "18" which may be set at such an angle as to lift the lever "15" outward by the resistance of the air when the disk "7" has attained the 10 desired speed.

Having now described my invention, what I claim is:

1. In an amusement apparatus, the combination with a base, of a central table secured thereto, a revoluble spacing disk concentric with said table, anti-friction balls engaging said base and supporting and projecting through said spacing disk, a passenger disk supported by the balls and concentric with said table, and means secured to said passenger disk and engaging said table whereby said passenger disk is rotated.

2. In an amusement apparatus, the combination with a base, of a central table secured thereto, a revoluble spacing disk concentric with said table, anti-friction balls engaging said base and supporting and projecting through said spacing disk, a passenger disk supported by the balls and concentric with said table, and rowing levers secured to said passenger disk and engaging said table whereby said passenger disk is rotated.

3. In an amusement apparatus, the combination with a base, of a central table secured thereto, radial flanges secured to the top of said table, a revoluble spacing disk concentric with said table, anti-friction balls engaging said base and supporting and projecting through said spacing disk, a passenger disk supported by the balls and concentric with said table, and rowing levers secured to said passenger disk and engaging

said radial flanges on said table whereby said passenger disk is rotated.

4. In an amusement apparatus, the combination with a base, of a central circular table secured thereto, a revoluble annular spacing disk concentric with said table, anti-friction balls engaging said base and supporting and projecting through said spacing disk, anti-friction rollers mounted on said spacing disk and engaging said circular table to hold said disk concentric therewith, an annular passenger disk supported by the balls and 55 engaging the outer surfaces of said rollers whereby it is held concentric with said table, and means secured to said passenger disk and engaging said table whereby said passenger disk is rotated.

5. In an amusement apparatus, the combination of a central table, radial flanges secured to the top thereof, a rotating passenger disk concentric with said table, rowing levers pivoted to said passenger disk, wheels 65 mounted on the ends of said rowing levers and adapted to engage and roll on said flanges whereby said passenger disk is rotated.

6. In an amusement apparatus, the combination of a fixed base, a rotating passenger disk, a brake shoe carried by said passenger disk and adapted to be brought into frictional engagement with said base, an actuating lever carried by said disk and engaging said shoe, a weight mounted on the end of 75 said lever and adapted to act thereon by its centrifugal force, and a wing mounted on said lever at an angle to the direction of rotation and adapted to act thereon by the resistance of the air.

In testimony whereof I affix my signature in presence of two witnesses.

ANSEL J. DAYTON.
